(57) **CLAIM**

The ornamental design for a rake, as shown and described.

DESCRIPTION

FIG. 1 is a front perspective view of a rake, showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view of a rake on a handle. The broken lines represent portions of the rake, and from no part of the claimed design.
